I claim the ornamental design for eyewear, as shown and described.

DESCRIPTION

FIG. 1 is a perspective view of eyewear showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof, the right side being a mirror image thereof; and,

FIG. 7 is a side elevation cross-section view thereof taken along line 7-7 in FIG. 4.

The broken lines immediately adjacent shaded areas represent bounds of the claimed design, while all other broken lines are unclaimed features. The broken lines form no part of the claimed design.
